DESIGN FOR A CROSSING SIGNAL

William Alonzo Billups, Grenada, Miss.

Application May 9, 1936, Serial No. 62,578

Term of patent 14 years

To all whom it may concern:

Be it known that I, William A. Billups, a citizen of the United States of America, residing at Grenada, county of Grenada, State of Mississippi, have invented a new, original, and ornamental Design for a Crossing Signal, of which the following is a specification, reference being had to the accompanying drawing, forming a part thereof, wherein:

Figure 1 is a front perspective view of a crossing signal showing my new design; and
Figure 2 is a side elevational view thereof.

The appearance of the opposite side of Figure 1 is substantially the same as the side shown.

I claim:

The ornamental design for a crossing signal as shown and described.

WILLIAM ALONZO BILLUPS.
